UNITED STATES PATENT OFFICE

90,760

DESIGN FOR A BOTTLE

Aaron Gluckman, New York, N. Y., assignor to Wise Shoe Co. Inc., New York, N. Y., a corporation of Delaware

Application April 25, 1933. Serial No. 47,890

Term of patent 3½ years

To all whom it may concern:

Be it known that I, AARON GLUCKMAN, a citizen of the United States of America, and a resident of New York city, New York, United States of America, whose post office address is 384 Fifth Avenue, New York city, New York, have invented a new, original, and ornamental Design for a Bottle, of which the following is a specification, reference being had to the accompanying drawing forming part thereof.

I claim:

The ornamental design for a bottle, as shown.

Dated at New York city, New York, this 13th day of April 1933.

AARON GLUCKMAN.
